UNITED STATES PATENT OFFICE.

SAMUEL P. BUSH AND JOHN H. McCORMICK, OF COLUMBUS, OHIO, ASSIGNORS
TO THE BUCKEYE MALLEABLE IRON AND COUPLER COMPANY, OF CO-
LUMBUS, OHIO.

BOLSTER FOR CARS AND CAR-TRUCKS.

SPECIFICATION forming part of Letters Patent No. 734,665, dated July 28, 1903.

Application filed July 31, 1902. Serial No. 117,843. (No model.)

To all whom it may concern:

Be it known that we, SAMUEL P. BUSH and JOHN H. McCORMICK, of Columbus, in the county of Franklin and State of Ohio, have invented certain new and useful Improvements 5 in Bolsters for Cars and Car-Trucks; and we do hereby declare the following to be a full, clear, and exact description of the invention, such as will enable others skilled in the art 10 to which it appertains to make and use the same.

Our invention relates to an improvement in bolsters for cars and car-trucks, its object being to provide a cast-steel bolster constructed 15 in such form as to render it strong and durable in use, of light weight, and capable of being manufactured at a comparatively small initial cost.

With these ends in view the invention consists in certain features of construction and arrangements of parts, as will be hereinafter described, and pointed out in the claims.

In the accompanying drawings, Figure 1 is a view in side elevation. Fig. 2 is a plan view. 25 Figs. 3, 4, and 5 are transverse sections taken, respectively, on the lines *a a*, *b b*, and *c c* of Fig. 1.

One member or plate 1 is downwardly inclined from the center-bearing 2 to the opposite ends of the bolster, while the other member or plate 3 is preferably made straight throughout its length. At each end of the bolster the top and bottom members are united by the short side webs 6 6 and the central webs 5, the latter extending from the outer end of the bolster inwardly to a point 9 and inside the inner ends of the side webs 6 6 and from the point 9 to the central web is divided into two ribs 10 10, which extend inwardly a considerable distance and merge into the top and bottom members. Depending flanges 11 are formed on the side edges of the top member 1 at the central portion of the bolster, while upwardly-projecting flanges 4 are formed on the side 35 edges of the bottom member 3. It will be observed that the side webs 6 6, central webs 5, and side flanges 11 and 4 are constructed so

that their ends overlap one another, so as together constitute continuous strengthening flanges or ribs extending the entire length of 50

The center column or pillar 2 is reinforced and strengthened by the longitudinally and transversely arranged webs 7 and 8, which connect the top and bottom members and 55 serve to strengthen the central portion of the bolster and its center-bearing.

A bolster of the form and construction above described is adapted to be made of cast-steel and produced at a low initial cost. The disposition of the metal entering into its construction is such as to produce a bolster of minimum weight and of great strength and 60 stiffness to resist transverse shocks and strains resulting from blows or shocks imparted to a 65 car in the direction of its length.

Having fully described our invention, what we claim as new, and desire to secure by Letters Patent, is—

1. A cast-steel bolster comprising top and 70 bottom members having side connecting-webs at the ends only and having central webs cast integral with opposite ends and terminating at points inwardly removed from the center of the bolster.

2. A cast-steel bolster consisting of top and bottom members each having cast integral therewith a vertical flange on each of its side edges which extend along the central portion of the bolster, substantially as set forth. 75

3. A cast-steel bolster consisting of top and bottom members having their ends connected by side and center webs and provided with side flanges all cast integral with the top and bottom members, substantially as set forth. 80

In testimony whereof we have signed this specification in the presence of two subscribing witnesses,

SAMUEL P. BUSH.
JOHN H. McCORMICK.
